UNITED STATES PATENT OFFICE.

EDGAR E. GREVE, OF BELLEVUE, PENNSYLVANIA.

PIPE TONGS.

Application filed November 17, 1921. Serial No. 515,757.

To all whom it may concern:

Be it known that I, EDGAR E. GREVE, a citizen of the United States, residing at Bellevue, in the county of Allegheny and 5 State of Pennsylvania, have invented certain new and useful Improvements in Pipe Tongs, of which the following is a specification.

This invention is for a pipe tong adapted 10 particularly for use in connection with pipes used in well drilling operations, and is known as a "back-up tong".

In connecting pipe sections used as drill stems in rotary drilling apparatus, and in 15 other uses where pipe sections are being coupled, it is necessary to hold one pipe section against rotation while a coupling or other member is being rotated thereon. The tong that is used to prevent rotation 20 of a section of pipe is called the "back-up tong", and practically any pipe tong can be used for this purpose. In so using a tong, as a back-up tong, the handle is moved against some stationary supporting structure 25 while the jaws are forced into binding or locked position. In order to release the tongs as now generally constructed, it is necessary to move the tong handle, and to do this, the supporter against which the tong 30 handle rests must be removed.

The present invention has for its principal object to provide an improved means for releasably holding the jaws together, which may be operated to release the jaws without 35 manipulating the tong handle in any manner.

My invention may be readily understood by reference to the accompanying drawing which illustrates my invention, and in 40 which:

Fig. 1 is a plan view of a tong embodying my invention, showing the jaws opened;

Fig. 2 is an end elevation showing the tong closed; and

Fig. 3 is a top view showing the jaws closed.

In the drawings, 5 is the handle of the tongs and it may be of any desired length. Spaced a short distance from the inner end 50 of the handle, is a fulcrum pin 6 on which is pivotally carried a jaw 7 having a slotted or bifurcated portion adjacent its pivot. Between the inner end of the handle 5 and the fulcrum pin 6, is a slot 8. The second jaw is designated by 9, and on one end thereof is a pin 10 having a roller 11 there-

about, which is received in the slot 8. The slotted or bifurcated part of jaw 7 is designed to receive the end of lever 5 and jaw 9 when the jaw is closed, as shown in Fig. 3. 60 In the jaw 7 are keys 12 which grip the pipe to hold it against rotation. With the arrangement shown, the jaws can be spread and contracted by manipulation of the lever 5. 65

On the free end of jaw 7 is a bifurcated or slotted extension which, for manufacturing purposes, is preferably in the form of two spaced apart plates 15, secured to the jaw in any suitable or preferred manner, as by rivets 16. Passing through the plates 15 and rotatable therein, is a pin 17 having squared outer ends projecting beyond the surface of plates 15. On the portion of the pin between the plates is an eccentric 18. 70

Having one end thereof between the plates 15 and journalled about the eccentric 18, is a locking link 19 having a transverse pin 20 extending therethrough near its free end. Projecting from the pivoted end of the link 80 is a lug 21, against which a compression spring 22, having its opposite end engaged in a recess in the jaw, bears. This spring acts to urge the locking link to its locking position hereinafter described. In the free 85 end of link 19 is a notch or recess 19'.

On the jaw 9 is a bifurcated extension 23 having a notch 24 therein. When the jaws 7 and 9 are in gripping or locked position, the link 19 is received in the cut-out portion or slot in the bifurcated extension 23 of jaw 9, and the pin 20, being received in the notch 24, holds the jaws from opening. 90

The projecting squared ends of pin 17 extend into squared openings in one end of each of straps 25. The other ends of straps 25 are connected by bolts 26, a block 27 being interposed between the two ends. Reciprocable in the block 27 is a locking pin 28 having a handle 29 secured thereto. The inner end of the pin is adapted to project into recess 19' in link 19, in which position it is normally held by compression spring 30. When the jaws are closed or locked, the end of pin 28 is in the recess 19' and the parts are in the position shown in Fig. 3. 100

When it is desired to open the jaws without moving lever 5, handle 29 is pulled outwardly until the inner end of pin 28 disengages recess 19'. Then the handle is swung through an arc of 180 degrees, the 110

straps 25, of course, moving therewith. This effects the rotation of pin 17 and eccentric 18. The movement of the eccentric 18 through a half circle effects a longitudinal movement of link 19, whereby cross pin 20 is moved out of the notch 24 in extension 23 of the jaw 9, and link 19 may then be moved through a limited arc sufficient to enable the jaws 9 and 7 to be spread.

In Fig. 1, the jaws are shown spread apart, and this figure illustrates how the tong is applied or removed from a pipe, designated A, when the jaws are so opened.

To lock the jaws about the pipe, they are pressed together and link 19 is moved into place. Spring 22 normally urges it to locking position. Then handle 29 is moved back through an arc of 180 degrees, reciprocating link 19 in the reverse direction, thereby pulling the jaws together. Owing to the leverage and pull which can be obtained by the handle and eccentric, the locking means may sometimes be used to draw the jaws together into clamping relation with a pipe without manipulating lever 5. When the handle has been moved to locking position, pin 28 will snap into recess 19' and hold the handle against movement.

The locking mechanism described is strong and durable, and is simple and positive in its construction and operation. It enables the jaws to be opened irrespective of the position of the tong handle or lever.

The mechanism furthermore prevents incidental opening of the jaws, as the parts are securely locked when the jaws are closed and once drawn together by the lock operating handle. The provision of the roller 11 on the pin 10 reduces the wear and friction between the parts and facilitates the operation of the tongs.

I claim:

1. A pipe tong comprising a lever having a pair of jaws thereon arranged to be opened and closed, a link pivotally secured to one of the jaws having means thereon for engagement with a shoulder on the other jaw to hold the jaws together, and means whereby the link may be given a reciprocable movement and a pivotal movement to move it into and out of locking engagement with the shoulder.

2. A pipe tong comprising a lever having a pair of jaws thereon arranged to be opened and closed, a pin having an eccentric on the free end of one of the jaws, a locking link carried by the eccentric, means on the locking link for engagement with the other jaw, and a handle fitted on the pin for effecting the rotation of said eccentric to produce a reciprocal movement of the link.

3. A pipe tong comprising a lever having a pair of jaws thereon arranged to be

opened and closed, a pin having an eccentric thereon in one of the jaws, a locking link pivoted at one end about the eccentric portion of the pin, means on the other end of the link for engagement with the other jaw, a lock operating handle fixed to the pin for rotating the eccentric whereby a reciprocable movement of the link may be effected upon swinging the handle through an arc, and means for normally locking said handle against movement when the locking link is in locked position.

4. A pipe tong comprising a lever having a pair of jaws thereon arranged to be opened and closed, a pin having an eccentric thereon in one of the jaws, a locking link pivoted at one end about the eccentric portion of the pin, means on the other end of the link for engagement with the other jaw, a lock operating handle fixed to the pin for rotating the eccentric whereby a reciprocable movement of the link may be effected upon swinging the handle through an arc, and means for normally locking said handle against movement when the locking link is in locked position, said means including a vertically reciprocable pin on the handle removably engaged in a recess in a part of the tool.

5. A pipe tong comprising a lever having a pair of jaws thereon arranged to be opened and closed, a pin having an eccentric thereon in one of the jaws, a locking link pivoted at one end about the eccentric portion of the pin, means on the other end of the link for engagement with the other jaw, a lock operating handle fixed to the pin for rotating the eccentric whereby a reciprocable movement of the link may be effected upon swinging the handle through an arc, and means for normally locking said handle against movement when the locking link is in locked position, said means including a vertically reciprocable handle yieldably engaged in a recess in the free end of the locking link.

6. A pipe tong comprising a lever, a pair of jaws pivotally connected at one end with the lever, a bifurcated extension on the other end of each of the jaws, a pin passing through the bifurcated extension of one jaw having an eccentric thereon, the eccentric being disposed between the two parts forming the bifurcated extension, a locking link having one end pivoted about the eccentric and having its other end arranged to be received in the bifurcated extension on the other jaw, projecting means on said link adapted to engage a part of the bifurcated extension on the second jaw to hold the jaws in closed relation, and means for moving the link for releasing and locking the jaws.

7. A pipe tong comprising a lever, a pair of jaws pivotally connected at one end with the lever, a bifurcated extension on the

other end of each of the jaws, a pin passing through the bifurcated extension of one jaw having an eccentric thereon, the eccentric being disposed between the two parts 5 forming the bifurcated extension, a locking link having one end pivoted about the eccentric and having its other end arranged to be received in the bifurcated extension on the other jaw, projecting means on said link 10 adapted to engage a part of the bifurcated extension on the second jaw to hold the jaws in closed relation, and means for moving the link for releasing and locking the jaws, said means including a handle connected 15 with said pin for rotating the pin together with its eccentric.

8. A pipe tong comprising a lever, a pair of jaws pivotally connected at one end with the lever, a bifurcated extension on the 20 other end of each of the jaws, a pin passing through the bifurcated extension of one jaw having an eccentric thereon, the eccentric being disposed between the two parts forming the bifurcated extension, a locking link 25 having one end pivoted about the eccentric and having its other end arranged to be received in the bifurcated extension on the other jaw, projecting means on said link adapted to engage a part of the bifurcated 30 extension on the second jaw to hold the jaws in closed relation, and means for moving the link for releasing and locking the jaws, said means including a strap fixed to said pin, a reciprocable handle on the outer end 35 of the strap, a locking pin reciprocated by reciprocation of the handle and adapted to engage a recess in the link to hold the parts against movement when the jaws are closed, said locking link being moved into and out 40 of locking position by movement of the handle to rotate said pin and eccentric.

9. A pipe tong comprising a lever having a pair of jaws thereon and a locking member including a pivoted and slidably link 45 on one of the jaws arranged to be recipro-

cated relatively to both jaws into and out of locking position, and means for maintaining the link in locked position.

10. A pipe tong comprising a lever having a pair of jaws thereon, a locking member 50 including a pivotally mounted link on one of the jaws arranged to be reciprocated relatively to both jaws into and out of locking engagement with the other jaw, an operating means including a handle for effecting a reciprocation of the link, and means on the handle for locking said link in locking position.

11. A pipe tong comprising a lever having a pair of jaws pivotally secured to the 60 lever, the pivot point for one jaw being spaced rearwardly of the pivot point for the other jaw whereby the jaws may be spread by movement of the lever in one direction from a normal position and closed 65 by movement of the lever in the opposite direction from the normal position, and means including a link for detachably engaging the free ends of the jaws for also drawing them into clamped position and 70 locking them in such position while the lever is in a fixed position.

12. A pipe tong comprising a lever having a pair of jaws thereon arranged to be opened and closed, an eccentric on one of 75 the jaws, a locking link carried by the eccentric, means on the locking link for engaging the other jaw, means for rotating the eccentric, and means for yieldably urging the link into locking position.

13. A pipe tong comprising a lever having a pair of jaws thereon arranged to be opened and closed, an eccentric on one of the jaws, a locking link carried by the eccentric, means on the locking link for 85 engaging the other jaw, and means for rotating the eccentric.

In testimony whereof I affix my signature.

EDGAR E. GREVE.
